(57) **CLAIM**

The ornamental design for a radio frequency identification (RFID) component, as shown and described.

DESCRIPTION

FIG. 1 is a perspective view of the radio frequency identification (RFID) component taken from the top, right, and front; and,

FIG. 2 is a top plan view of the radio frequency identification (RFID) component of FIG. 1.

The surface shading of the RFID component represents the metallic character of the surfaces. The RFID component is shown with a symbolic break in its length. The appearance of any portion of the article between the break lines forms no part of the claimed design. The bottom plan view is a mirror image of the top plan view.

1 Claim, 1 Drawing Sheet

FIG. 1

FIG. 2
